UNITED STATES PATENT OFFICE.

NICHOLAS DEDRICK, OF MANITOWOC, WISCONSIN.

RIVET CUTTING AND UPSETTING MACHINE.

1,149,737.

Specification of Letters Patent. Patented Aug. 10, 1915.

Application filed November 6, 1914. Serial No. 870,577.

To all whom it may concern:

Be it known that I, NICHOLAS DEDRICK, a citizen of the United States, and resident of Manitowoc, in the county of Manitowoc 5 and State of Wisconsin, have invented certain new and useful Improvements in Rivet Cutting and Upsetting Machines; and I do hereby declare that the following is a full, clear, and exact description thereof.

10 My invention refers to riveting mechanism and has for its object to provide a simple, durable and effective rivet cutting and heading mechanism, the construction and arrangement being such that a reciprocative head, on its working stroke, successively effects a clamping engagement of material worked upon carrying a rivet between said head and a fixed anvil. The next operation severs the protruding end of the rivet by 15 shear mechanism and the final operation upsets the severed head of said rivet by a blow independent of the movement of said head.

Specific objects of my invention are to provide a two-part reciprocative head comprising a presser member and an independently movable riveting member; to provide a power actuated plunger in connection with the riveting member and means for controlling the same; to provide a cutting 20 shear associated with the presser-foot head member, and means in connection with the riveting head member for controlling said shear; to provide a plunger and a correlated spring-controlled trip hammer for generating 25 the riveting power; to provide a lock and release mechanism for said spring-controlled trip hammer under control of movement of one of the head members; to provide a yieldable rivet-centering plunger in 30 connection with the presser-foot member, whereby a rivet is more effectually centered under the plunger mechanism; to provide a cushion connection between the presser-foot members and means for positively actuating 35

40 the riveting member of said head, whereby a cushion effect is had with relation to the presser-foot member when the latter is seated upon the article being worked upon, which article is seated upon an anvil; to 45 provide interchangeable cutting blades for the shears, and to provide a double track cam mechanism in connection with the head riveting member for operating the shears, the cam and associated mechanism being so 50 designed with relation to said shears that, 55

upon the working stroke of the head, the presser-foot is first caused to engage the goods and clamp the same upon a mandrel and, following this movement, the cutting blades of the shears are caused to close upon and sever the rivet to be operated upon, which movement is followed by a slight expansion of the cutting blades to permit a clearance for the plunger mechanism that is then brought down by impact of the trip 60 hammer to upset the severed end of said rivet, it being understood that the trip hammer mechanism has been previously loaded by the initial downward travel of the two members comprising the head. 65

70 With the above and other minor objects in view the invention consists in certain peculiarities of construction and combination of parts as set forth hereinafter with reference to the accompanying drawings and 75 subsequently claimed.

In the drawings, Figure 1 represents a side elevation of a riveting machine embodying the features of my invention, with parts in section as indicated by line 1-1 80 of Fig. 2; Fig. 2, a detailed face view of the head portion of said machine with parts removed and parts in section as indicated by line 2-2 of Fig. 1; Fig. 3, a detailed cross-section of the riveting machine head, the 85 section being indicated by line 3-3 of Fig. 1; Fig. 4, a detailed cross-section of the head, the section being indicated by line 4-4 of Fig. 1 to particularly illustrate a rivet centering or gaging plunger, and Figs. 90 5, 6 and 7 illustrate enlarged detailed sectional views of the working elements of the head showing the positions they assume in the several steps in the operation of cutting and riveting for confining a series of layers. 95

In the exemplification of my invention shown by the drawings, the same is particularly designed for use in connection with riveting the metallic binder strips of small articles such as leather pocketbooks, purses 100 or the like, but, it is obvious that the essential elements of the machine may be employed for cutting and riveting in connection with the manufacture of a variety of articles not mentioned. 105

Referring by characters to the drawings, 1 represents a bed-plate having an anvil 2 projecting upwardly therefrom, the same being provided with a laterally projecting socketed horn 2' that serves as a convenient 110

rest for the articles being operated upon. Rising from the rear portion of the bed is a neck 3, which neck supports a base 4 having a vertically disposed dovetailed channel 4' in its face. The channel 4' is provided for the reception of the dovetailed flanges 5 comprising part of a presser-foot member 6 constituting one member of a reciprocative head. The companion head element consists 10 of a riveting member 7, the side walls of which are dovetailed for engagement with a correspondingly dovetailed channel 7' that is arranged longitudinally of the presser foot member. Thus it will be seen that the 15 presser-foot member is slidably mounted within the base and the riveting member is correspondingly slidably mounted within the presser-foot member of the head. The upper end of the riveting member is formed with 20 a cap 8, the rear end of which extends through a slot 9 that is formed in the upper end of the presser-foot member 6. A plunger piston 10 projects from the rear end of the cap 8 and is slidably fitted into a 25 dash-pot 10' that is formed in the body of said presser-foot member. Interposed between the bottom of the dashpot and the plunger piston 10 is a cushion spring 10', whereby a cushioning or yielding connection 30 is effected between the head members, downward movement of the plunger piston being limited by engagement of the cap with the lower face of the presser-foot slot, while movement in the opposite direction of said 35 piston is limited by a key-pin 11 which engages a slot 11' that communicates with the dashpot chamber. The riveting member is provided with a lever-receiving slot 12 above its cap portion 8 for the reception of 40 the headed end 13 of an actuating lever 14, which lever is suitably fulcrumed between ears 3' that project upwardly from the neck 3 that forms part of the frame of the machine. The rear end of this actuating lever 45 is connected by a link 14' to a spring-controlled foot treadle, not shown, whereby the actuating lever is controlled. It should be understood, however, that, while I have mentioned one means of operating the actuating lever 14, power may be applied to the 50 same in any suitable manner other than that shown, or other means than a lever may be employed for imparting a reciprocating motion to the composite head previously mentioned. The lower end of the presser foot member 6 has secured thereto a stop block 6' which is adapted to engage the rear bottom edge of the base 4, whereby upward movement of the presser-foot member is 55 limited. Thus the spring-control in connection with the foot treadle, not shown, will normally hold the head suspended in the position as illustrated in Fig. 1 of the drawings, in which position the upper portion 60 of the cap 8 extending from the riveting 65

member engages the upper wall of the slot 9 that is formed in the presser foot member 6, whereby the latter is positively held at the terminal of its idle stroke. The riveting member of the head has fixedly secured thereto a barrel 15 having upper and lower thimbles 15', 15'', respectively, and slidably mounted in the barrel is a stem 16 having a head 16' that is guided in the bore of said barrel. Surrounding the stem 16 and interposed between the head 16' and the thimble 15' is a coiled spring 17, which coiled spring exerts downward pressure upon the stem, whereby its head is normally held in engagement with the bottom thimble 15'' of the barrel, the said mechanism constituting a trip hammer. The upper end of the trip hammer stem 16 terminates with a notched nose 16'', the notch being adapted to engage a correspondingly notched nose 18' of a 85 trigger 18, the said trigger being fulcrumed between ears 19 that project from the upper end of the presser foot member 6. The trigger is guided at an intermediate point by passing through a slot that is formed in 90 a forwardly projecting lip 8'' of the cap 8 of the riveting member 7 and said trigger is also normally held in locking engagement with the nose of the stem 16 by a leaf spring 20 which is secured to the upper end of the aforesaid presser foot member. The trigger is also formed with a cam lug 21, which cam lug is engaged by the lip 8'' of the riveting member 7 when said riveting member reaches the approximate end of its working 95 stroke, this portion of the stroke being independent of any movement of the presser-foot member 6 of said head. 100

A fulcrumed stud 22 extends forwardly from the lower portion of the presser-foot member 6 and mounted upon said stud are oscillatory arms 23 that constitute a rivet-cutting shear. The upper ends of the arms are preferably provided with anti-friction rollers 23', which rollers engage double tracked cams in the form of slots 24, the same being developed from plates 25, which plates are secured by screws 25' to the face of the riveting member 7 as best shown in Fig. 2. The retaining screws, as shown, are preferably passed through elongated openings in the cam-plates, whereby said cam-plates are capable of slight adjustment and this fine adjustment is determined by manipulating a tapered head master screw 25'' 115 and fixed by firmly setting the screws 25' that serve to bind the companion cam-plates, it being understood that said plates may, in some instances, be formed integral with each other, such construction as shown and described in detail being for the purpose of economy in the manufacture. 120

The lower short legs of the shear arms 23 are spaced apart and have dovetailed grooves 26 therein for the reception of cor- 130

respondingly dovetailed tongues 26', which tongues project from the rear faces of cutting blades 27. Thus said blades can be removed for renewal or for sharpening purposes and when fitted in the dovetailed grooves, they are locked by binding screws 27', the said blades being composed of hardened steel.

As best shown in the magnified views, Figs. 5 to 7 inclusive, the lower faces 27" of the blades, in conjunction with the ends of the shear arms, constitute presser feet for engagement with the article to be worked upon, the said presser foot surfaces being 15 slightly crowned upward to a cutting edge, whereby the rivet body A is severed at a point slightly above the material through which the rivet projects for the purpose of providing suitable metal whereby an upset 20 head may be formed.

The pivot stud 22, which carries the shear arms, is, as shown, centrally bored for the reception of the shank 28 of a guide box 28', the shank of said guide box being 25 firmly held by a screw threaded locking plug 28" which enters the recessed stud and engages the threaded end of the aforesaid shank.

Reciprocatively mounted within the guide- 30 plug 28' and the barrel thimble 15" is a riveting plunger 29, the bottom end of which, as best shown in Fig. 7, is preferably formed with a concaved rivet heading recess 29'. A collar 30 is mounted adjacent to the upper end of the plunger 29 and between said collar and the top portion of the box 28' there is interposed a light coiled spring 31 adapted to exert sufficient pressure to hold the plunger in its receded position of rest with relation to the guide box 28', which pressure also causes the upper end of said plunger to project within the trip-hammer barrel when the bottom of said barrel is freed from engagement with the 45 head 16'. Between the collar 30 and the lower face of the barrel-thimble 15 is interposed a short section of buffer spring 31'.

In order to facilitate alinement of a rivet A with the spring-controlled riveting plunger 29, I provide a "feeler" or guide plunger 32, which guide plunger is arranged to have yielding play at a right angle to the riveting plunger and is mounted in a sleeve 33 that is carried at the extreme end of the 55 presser-foot member 6. The said sleeve is in screw-threaded union with a concentrically bored recess 33' that is formed in the extreme end of the foot member, the recess being intersected by transverse slots 34. 60 These slots are adapted to receive a guide pin 35 that projects from the plunger, whereby the latter is held against rotary movement in its seat. The plunger is normally held forward by a coiled spring 36 which 65 engages the rear end of the plunger and

abuts a screw plug 36' that is in threaded union with the rear end of the bore 33'. The forward exposed end of the plunger carries a rivet guiding head 32' which is formed with a backwardly flared rivet-centering socket 32".

Referring to the drawings and especially Figs. 5 to 7 inclusive, in the operation of my invention, for example, when the metal binders of a pocketbook are to be riveted, 75 the article is seated upon the anvil horn, as best shown in Fig. 1. The article, in this exemplification of the operation, is a fragment of a pocketbook comprising an outer leather jacket a and an inner pocket strip b, the edges of which are fitted together and seated within an L-shaped binder c. A flat clamping binder c' is then seated to the L-shaped binder and the series of rivets in the

form of small nails are then passed through 80 apertures in the several elements, as shown, the said rivets being disposed at suitable intervals apart and the frictional engagement of the rivets is sufficient to hold them in the position as illustrated in Fig. 1. The 85

crowned head of the rivet, as shown, is seated within the head socket 2' of the anvil horn, which socket is alined with the trip hammer mechanism and plunger and the extreme end of the rivet element will engage a socket 32" in the yieldable rivet-guiding plunger 32'.

The operator now manipulates the foot treadle mechanism, whereby the actuating lever 14 will cause the reciprocative head to move down bodily 90 until the presser-foot faces of the shears abut the material to be operated upon, whereby said material is clamped with relation to the anvil horn. Thus the presser-foot member 6 of the head has completed 95

its movement and the actuating lever 14 which engages the riveting member 7 of the head now causes said riveting member to move downward independent of the arrested member and, in describing said movement, attention is called to the fact that the cushion mechanism embodying the spring 10' will exert a gradual increasing clamping 100 force upon the material. In the initial independent movement of the riveting element 105 of said head, owing to the configuration of the cam slots 24, the cutting blades of the shears will be brought together, whereby the rivet body will be cut off, as shown in Fig. 6 of the drawings. Further movement of the riveting member cams will cause the cutting blades to recede, whereby clearance therebetween is had to permit a riveting 110 operation. This operation takes place at approximately the finish of the working 115 stroke.

In connection with the riveting movement attention is called to the fact that, as the riveting member 7 starts upon its independent travel downward, the trip hammer spindle 120

125

130

16 will be held from further movement by its engagement with the nose of the trigger 18. Hence the barrel carried by the riveting member 4 travels downwardly upon the now 5 fixed stem 16, whereby the coiled spring 17 is compressed or loaded above its normal tension. Thus it will be seen that when the riveting member has approximately completed its working stroke, the lip 8" of said 10 member will engage the cam lug 21 of the trigger, whereby the same is tripped or released from its engagement with the nose of the stem 16 and the compressed spring will now cause the trip hammer to shoot 15 downward, the impact being against the upper exposed end of the plunger 29. Owing to the fact that the plunger spring 31 is of quite delicate tension, the hammer-like power applied to said plunger will cause 20 the same to strike the exposed end of the rivet A a blow sufficient to upset the same in any desired manner, whereby the metallic binder elements of the intermediate bodies are firmly riveted together and, in this sudden 25 downward movement of the riveting plunger, it will be noticed that its upsetting end will travel through the socket 32' of the rivet guiding plunger head, whereby the latter will recede slightly. The work is now 30 shifted to align another rivet under the mechanism and the operation repeated so on throughout in order to cut off and upset the series of rivets, the feeding movement by hand being similar to that used in connection 35 with shoe-operating or stapling machines. With each recovery movement of the head it is obvious that the two elements comprising the latter will lift successively in such manner that the riveting member, 40 which is positively operated, will engage the presser-foot member and bring the parts at rest with relation to each other to the position shown in Fig. 1 of the drawings, whereby the nose 16" of the trip hammer 45 spindle 16 will again effect interlocking engagement with the nose of the trigger 18 which has slight rearward yield to permit such engagement.

From the foregoing description it is obvious that for the coiled spring 17, which constitutes a power storage means whereby impact is given to the riveting plunger, other motive force may be employed.

I claim:

55 1. A rivet-cutting and upsetting mechanism comprising a presser-foot member adapted to come to rest upon the work to be operated upon, a positively actuated riveting member in slidable union therewith, a power-controlled upsetting plunger carried 60 by the riveting member, means associated with the presser-foot member for delaying movement of the spring-controlled plunger as said riveting member advances coincident 65 to the presser-foot member coming to rest,

whereby power is stored for actuating the plunger; means associated with the riveting member for releasing the delayed spring-controlled plunger as said riveting member continues its movement, and a cam-actuated cutting shear affixed to the presser-foot. 70

2. A rivet cutting and upsetting mechanism comprising two members in slidable union constituting a head, a fixed base into which the head is slidably mounted, means for reciprocating the head, an upsetting plunger carried by one of the members, means for imparting a riveting impact thereto independent of the head reciprocating means, a shear carried by one of said members, a shear-actuating cam carried by the other member, and means carried by one of the head members for controlling the plunger impact means. 75 80

3. A rivet cutting and upsetting machine comprising a presser-foot member adapted to come to rest upon work to be operated upon, a positively actuated riveting member in slidable union therewith, a power-controlled trip hammer carried by the riveting member, a plunger coöperative therewith, means associated with the presser-foot member for retarding the trip-hammer whereby power is stored for imparting movement thereto, means associated with the riveting member for releasing the hammer retarding means, and a cam-actuated cutting shears affixed to the presser-foot. 90 95

4. A rivet cutting and upsetting machine comprising a presser-foot member and a riveting member, the said members constituting a head, reciprocative means engageable with the members whereby the riveting member is caused to travel a greater distance than the presser-foot member, a spring-controlled trip hammer carried by the riveting member, a plunger coöperative therewith, a trigger carried by the presser-foot member engageable with the trip hammer, trigger release means carried by the riveting member, and a cam-actuated cutting shear affixed to the presser-foot member. 100 105 110

5. A rivet cutting and upsetting machine comprising a bed having an anvil extending therefrom, a vertically disposed base member carried by the bed, a presser-foot member in slidable union with the base having a slot adjacent to its upper end, a riveting member in slidable union with the presser-foot member, an actuating lever extending through the presser-foot slot in engagement with the riveting member, a cam-actuated cutting shear carried by said presser-foot member positioned over the anvil, a spring-controlled trip hammer mounted upon the riveting member having a stem provided with a locking nose, a riveting plunger engageable with the trip hammer, a trigger carried by the aforesaid presser foot member for locking engagement with the nose 115 120 125 130 135

stem of the trip hammer, and releasing means for the trigger carried by the presser-foot member.

6. A rivet cutting and upsetting machine comprising a presser-foot member and a riveting member in slidable union therewith the said members constituting a head, means for imparting independent movement to the head members, means for cushioning the 10 relative movement of said head members, a shear mechanism carried by the presser-foot member, means for actuating the same extending from the riveting member, a spring-controlled riveting plunger carried by said riveting member, a spring-controlled trip hammer adapted to engage the riveting plunger, means for effecting locking engagement between the trip hammer and presser-foot member, and 15 means for releasing the locking mechanism coincident to independent movement of the riveting head member.
7. A rivet cutting and upsetting machine comprising a presser-foot member and a riveting member in slidable union with each 20 other, means for imparting independent sliding movement to the head members, a stud extending from the presser-foot member, oscillatory shear arms mounted upon the stud, cutting blades carried by said arms, a double tracked cam-plate carried by the riveting member engageable with the arms whereby movement of the cutting 25 blades is controlled in both directions, a spring-controlled trip hammer, guides

therefor affixed to the riveting member, a riveting plunger positioned under the trip hammer, a guide for the riveting plunger associated with the riveting member, a second guide for said plunger associated with 40 the shear-blade stud, a trigger mechanism for effecting locking engagement with the trip hammer, and means for releasing the trigger carried by the aforesaid riveting member. 45

8. A rivet cutting and upsetting machine comprising a presser-foot member and a riveting member, the said members constituting a head, reciprocative means engageable with the members whereby the riveting member is caused to travel a greater distance than the presser-foot member, a spring-controlled trip hammer carried by the riveting member, a plunger coöperative therewith, a trigger carried by the presser-foot member engageable with the trip hammer, a stud extending from the presser-foot member, a guide-box carried by the stud for the plunger, oscillatory cutting blades mounted upon the stud, and a cam carried 55 by the riveting member for actuating the cutting blades.

In testimony that I claim the foregoing I have hereunto set my hand at Manitowoc in the county of Manitowoc and State of Wisconsin in the presence of two witnesses. 60
